METHOD OF OPERATING COKE OVENS

Roger Francis Richardson, Buffalo, N. Y., assignor to Semet-Solvay Company, New York, N. Y., a corporation of New York

Application October 24, 1929. Serial No. 402,103

1 Claim. (Cl. 202—12)

This invention relates to coke ovens and more particularly to the generation of the heat necessary to coke the charges in the coking chambers of a coke oven battery in which the charges are coked by indirect transfer of heat from the combustion flues flanking the coking chambers, in which flues the heat is generated, to the charge of coal or other material in the coking chambers.

The invention comprehends processes for coking a charge of coal or other cokable material in coke oven having alternate horizontal coking chambers and heating walls preferably composed of series-connected horizontal combustion flues as in the Semet-Solvay coke oven battery, which processes involve burning petroleum oil or coal tar oils in the flues to generate the heat necessary for coking the charge. The invention also includes coke ovens designed to practice such processes.

One object of this invention is to provide a coke oven battery in which the heat necessary to coke the charge may be generated in the flues by burning either liquid hydrocarbon material such as petroleum oil or coal tar oils or gas, the coke oven battery being so designed that the heating medium supplied to the flues may be readily changed from gas to oil or vice versa by simply manipulating suitable valves provided for this purpose. The gas and oil burners in accordance with this invention are so constructed that a mixture of gas and oil may be fed to the flues or, as above indicated, only gas or only oil fed to and burned in the flues. Thus the operation of the coke oven battery is rendered much more flexible than existing coke oven batteries which are adapted to burn only gas in the flues, as in accordance with this invention the gas heretofore necessarily burned in the coke oven flues to generate heat for coking the charge is, if market conditions permit, rendered available for market purposes. Further, either the entire amount of gas generated by the carbonization of the coal charge or only so much of the gas as market conditions permit may be marketed. In the latter case the surplus gas is burned in the flues, and if the amount of gas is not sufficient to coke the charge, oil is fed to and burned in the flues to supply the deficiencies.

In the accompanying drawing forming a part of this specification and showing for purposes of exemplification a preferred form and manner in which the invention may be embodied and practiced without limiting the claimed invention to such illustrative instance—

Fig. 1 is a fragmentary vertical section partly

in elevation through the flues and the regenerator of a horizontally flued coke oven of the Semet-Solvay type; and

Fig. 2 is a fragmentary detailed section partly in elevation through one end of the flue showing on an enlarged scale a gas and oil burner constructed in accordance with the present invention.

In its present embodiment the invention is incorporated in a horizontally flued coke oven battery and for convenience the present description will be confined to this embodiment of the invention. Features of construction and operation are, however, capable of other available applications, for example, to apparatus generally useful for coking materials and, consequently, the invention is not confined in its scope to the specific use and embodiment herein described as an illustrative example.

Referring to the drawing, 1 indicates a horizontal coke oven battery of the well known Semet-Solvay type which as usual is formed of alternate horizontal coking chambers and heating walls 2. Each heating wall is composed of a series of zigzag horizontal combustion flues 3, 4, 5, 6 and 7, each extending from one end of the coking chamber to the other. The lower horizontal flue 3 of each heating wall communicates through a port 8 with a crosswise extending regenerator 9 beneath the coking chamber and parallel thereto. The top horizontal flue 7 of each heating wall communicates through port 11 with a flue passage (not shown) which communicates with an adjacently located regenerator. Each regenerator 9 is provided with a sole channel 12 through which, during the inflow cycle of operation, air is fed into and through the regenerators to the flues. Upon reversal, during the outflow cycle of operation, waste gas or products of combustion pass from the flues through the regenerators 9, imparting their heat to the checkerbrick therein, and then through the channels 12 into passages 14 connected to chimney flue 13. Suitable automatically operated valves diagrammatically indicated at 15 control each passage 14 between each sole channel 12 and the chimney flue 13. These valves when in the position shown in the drawing, permit flow of air into the regenerators and shut off the connecting passages 14 between the chimney flue 13 and the regenerators. Upon reversal, the valve 15 is positioned to close the port through which air enters the regenerators and places the sole channels 12 in communication with chimney flue 13. The above described structure represents but one type of horizontally

flued oven battery and per se forms no part of this invention. Accordingly, this oven battery has only been described in sufficient detail so that the relation of my invention thereto will readily be understood by those skilled in the art. Further, it will be understood that this invention is applicable to other types of oven batteries and is not confined to a regenerative oven battery, i. e., the invention is applicable to batteries in which recuperators are utilized instead of regenerators or in which other means for utilizing the waste heat of the products of combustion are provided.

Gas mains 16, preferably running the whole length of the oven battery, are positioned one at each side of the battery. Gas pipes 17, preferably one for each series of flues in each heating wall, lead from the gas mains 16 through a gas T 18 positioned directly opposite the gas burner opening 19 in the flue passage connecting flues 3 and 4 to a gas T 21. Gas burner pipes 22 extend from the gas T 21 into the flue passage connecting flues 5 and 6 and a gas burner 23 extends from the T 18 into the flue passage connecting flues 3 and 4. Similarly, on the other side of the battery, gas burners 24 are positioned in the flue passage extending between flues 4 and 5 and gas burner 25 is positioned in the flue passage between flues 6 and 7. As is customary, diaphragm valves 26 are inserted in the gas lines 17 before the gas burners to regulate the flow of gas to the burners. As the structure of the gas and oil burners for each side of the battery is the same, for the sake of brevity and clearness, the structure and operation of the burners on only one side of the battery will be described herein, those on the right side, viewing Fig. 1 of the drawing, being broken away to permit illustration of the invention on a larger scale than would otherwise be possible.

In accordance with this invention two mains 28 and 29 are disposed the full length of the battery on each side thereof. Main 29 is connected to a suitable source of air under pressure sufficient to supply air to the burner nozzle under a pressure of approximately one-half pound per square inch and main 28 is supplied with oil under a constant head from a tank 30 which preferably extends above the top of the battery. The oil in tank 30 is maintained at a fixed level by means of a float valve 31, of well known type, in the valve control supply line 36, thus providing a constant pressure gravity flow to the oil main 28. From the tank 30 the oil passes through a conventional strainer 32 through pipe 33 into main 28. Valve 34 is placed in the strainer line and a by-pass main 37 having a valve 36 therein is provided to permit the cutting of the strainer 32 out of the line of oil flow for cleaning or other purposes whenever desired.

From the oil main 28 a riser pipe 38 extends vertically along each series of flues and similarly from the air main 29 a riser pipe 39 extends vertically along each series of flues. The oil riser pipe 38 at a point opposite the gas burner 23 has a T fitting 40 and has an elbow fitting 41 threadedly mounted or welded to the top thereof. Oil burner nozzles 42 are connected to each fitting 40 and 41. The nozzles 42 are each provided with a needle valve 43 of any suitable type to control the flow of oil therethrough.

In a like manner, the air riser pipe 39 is provided with a T fitting 46 at a point opposite the lower gas burner and a T fitting 47 at a point opposite the upper burner. Air burner pipes 49 are connected to the T fittings and extend within

the respective gas burners terminating at a point before the extremity of the gas burner extending within the flues. It will be noted that in accordance with this invention, the heretofore usual gas T's positioned opposite the gas burner openings are modified to provide a stuffing box or bushing 45 through which the oil burner assembly extends. As above indicated, each oil burner is composed of a valve control inner oil pipe, preferably a copper tube of about $\frac{1}{16}$ " outside diameter, and a valve control outer air pipe of about $\frac{1}{4}$ " inside diameter, this assembly of pipes extending through the stuffing box 45 into the usual gas burner pipe, both the air and oil pipes being concentrically positioned with respect to the gas burner pipe. As will be seen from the drawing, the tip of the air pipe is of conical shape and extends a slight distance beyond the tip of the inner oil pipe. This feature, it has been found in practice, causes the air to atomize and disperse the oil forming an oil mist which passes into the oven flues and is burned therein, combustion being supported by the air fed through the oil burner and the preheated air fed into the flues from the regenerator associated with the flues. Thus there results a long flame through the flues which in operation has been found to give satisfactory coking temperatures throughout the full length of each horizontal flue.

In operation, if demands for gas are low so that there is sufficient surplus gas to provide the necessary heat for coking the charge, coke oven gas is fed from the main 16 and burned in the flues, the air to support combustion, preheated in passing through the regenerators, being fed to the flues through port 8 leading into the bottom flue 3. If, however, the demand for gas is equal to the entire output of the battery, the valve controlling the gas main 16 is closed and slip blanks are placed in the diaphragm valves 26 to disconnect the gas burners from the gas mains. Oil, as above described, is then fed from tank 30 under constant pressure through strainer 32, pipe 33 into main 28 and air under pressure is supplied from a suitable pump (not shown) to main 29, the air and oil thus being fed through the oil burners in each flue to individual flues and burned therein. The auxiliary air necessary to support combustion is supplied from the inflow air régénératôrs beneath the coking chambers associated with the flues in question. The resultant products of combustion pass from the flues into and through the outflow regenerators 9 and thence through the chimney flue 13. As usual, the flow through alternate sets of regenerators is reversed so that the regenerators serving as inflow regenerators during one cycle of operations to preheat the air serve as outflow regenerators during a succeeding cycle to abstract the waste heat from the products of combustion passing therethrough.

In practice, in an oven battery of the Semet-Solvay type equipped with oil burners as described herein, it was found that satisfactory coking temperatures were obtained by burning oil in the flues as above described. The oil burner consumed but a small quantity of liquid fuel in operation, thus making it possible to supply all the burners necessary to heat the flues and resulting in substantially even temperatures throughout the flues.

It will be noted that the oil burner of this invention may be readily fabricated as it is constructed of standard pipe fittings. Also this oil burner is so designed that it can be installed

in the gas T's of standard horizontal flue ovens. Existing installations can, therefore, be readily modified to practice the present invention.

It will also be noted that in accordance with 5 this invention the heating medium supplied to the flues may readily be changed from gas to oil and vice versa by simply manipulating the valves controlling the feed of gas to the gas burners and those controlling the feed of oil 10 and air to the oil burners. Further, if desired, a mixture of oil and gas may be burned in the flues by simply feeding gas through mains 17 to the gas burner pipes 22 and oil and air through the oil burners. Thus, if the surplus gas is not 15 sufficient to generate the necessary heat for coking the charge, the deficiencies may be supplied by feeding oil to the flues. Burning a mixture of oil and gas in the flues also makes it possible to use lean gas such as producer or blast furnace 20 gas which may or may not be preheated, the oil acting in the nature of a carburetted medium to enrich the gas, increasing the B. t. u. content thereof to a sufficient extent to permit the obtaining of satisfactory coking temperatures in 25 the flues.

The invention herein is applicable not only to the burning of petroleum or coal tar oils in the

flues but also to the burning of other liquid fuels such as fluid coal tar or petroleum tar, etc. and the term liquid hydrocarbon material is used herein to include all such liquid fuels.

The invention as hereinabove set forth is embodied in a particular form of construction but may be variously embodied within the scope of the following claim.

I claim:

The method of operating a regenerative coke oven battery, comprising alternate, horizontally elongated, coking chambers and heating walls arranged side by side, the heating walls being composed of horizontal, zig-zag, series-connected, combustion flues, which involves generating the heat necessary to coke the charge of cokable material in the coking chambers by simultaneously introducing into the ends of said flues air and oil from the group: coal tar oil and petroleum oil, thus atomizing and dispersing the oil forming a mist extending throughout the length of said flues, and simultaneously passing preheated air from the regenerators through said flues to support the combustion of said oil mist in said flues, which combustion takes place in long flames 100 throughout the length of said flues.
